UNITED STATES PATENT OFFICE.

EMERY M. MCVICKER, OF MILWAUKEE, WISCONSIN, ASSIGNOR TO J. F. MCVICKER, OF MILWAUKEE, WISCONSIN.

RAIL FASTENER.

Application filed May 22, 1922. Serial No. 562,599.

To all whom it may concern:

Be it known that J. EMERY M. MCVICKER, a citizen of the United States, residing at Milwaukee, in the county of Milwaukee and 5 State of Wisconsin, have invented a certain new and useful Improvement in Rail Fasteners, of which the following is a full, clear, concise, and exact description, reference being had to the accompanying drawings, 10 forming a part of this specification.

This invention relates to rail fasteners and, particularly, to that type involving the use of tie plates.

One object of the present invention is the 15 provision of an improved fastener for securely retaining the rail against creeping as well as transverse play.

Other objects and advantages will herein-after appear.

20 Two embodiments of the invention are illustrated in the accompanying drawings, in which:

Figure 1 is a plan view of a tie plate and 25 rail fastener constructed in accordance with the present invention.

Figure 2 is a sectional view taken substantially on the line 2—2 of Figure 1.

Figure 3 is a side elevation, partly in section, of the parts shown in Figure 1.

30 Figure 4 is a perspective view of a rail clip employed with the tie plate of Figures 1, 2 and 3.

Figure 5 is a fragmentary plan view of a tie plate and rail fastener of somewhat different form embodying novel features of 35 the present invention.

Figure 6 is a sectional view taken substantially on the line 6—6 of Figure 5.

The rail fastener of Figures 1, 2 and 3 40 includes a tie plate 10 shown positioned beneath a rail 11 of standard form and resting upon a wooden tie 12 of usual construction. Certain portions 13 of the edges 14 of this tie plate are bent upwardly out of the plane 45 of the plate to provide substantially upright shoulders 15 for sustaining the side thrusts imposed on the rail. Other bent up portions 16 serve a similar purpose and also serve to retain the rail clips 17 against upward displacement in a manner to be hereinafter described.

50 Adjacent each pair of bent up portions 16 a clip receiving opening is provided, comprising a relatively narrow portion 18 extending inwardly beneath the base of the

rail and an outer portion 19 spanning the distance between the bases of the bent up portions 16 and extending outwardly therebeyond. The outer or rear wall 20 of each opening 19 is preferably cut away or shaped 60 to provide a pair of oppositely inclined walls 21 for cooperation with a spike 22 in a manner to be hereinafter described.

Each clip 17 is substantially U-shaped having upper and lower jaws 23 and 24 for 65 embracing an edge of the rail base, the lower jaw 24 being received in the narrow portion 18 of an opening in the tie plate. The base portion of each clip is preferably thickened and shaped to provide a pair of inclined 70 faces 25 for engagement beneath the inclined lower surfaces 26 of a pair of bent up portions 16. The bent up portions 16 thus constitute in effect undercut walls which co-operate with the faces 25 of a clip to retain 75 the clip against upward movement. The outer portion 19 of each opening in the tie plate is of sufficient depth to permit outward movement of the clip so that the faces 25 may clear the bent up portions 16 and thus permit the withdrawal of the clip upwardly 80 therefrom.

Each clip 17 is retained in rail gripping position by any appropriate means, such as 85 a spike 22 driven through the opening 19 into the tie, and by which the clip is forced inwardly into rail gripping position. It will be noted that in this position, the spike is wedged between the recessed portion of the rear wall 20 of the opening 19 and the rear face 27 of the rail clip. Should the rail tend to creep in either direction, dragging the tie plate with it, one of the inclined walls 21 would be brought into play to force the spike toward the clip and consequently 90 force the clip into still tighter contact with the rail.

The tie plate and fastener shown in Figures 5 and 6 is similar in many respects to 95 that above described and is substantially identical with that shown in Figures 4, 5, 6 and 7 of the drawings forming a part of my copending application, Serial No. 507,912, filed October 15, 1921. It includes a tie plate 10' having an opening 19' extending beneath the rail and having a pair of bent up portions 16' overhanging the opening. A clip 17' is positioned in this opening and is provided with upper and lower jaws 23 and 24 embracing the edge of the rail base 100 105 110

and inclined faces 25 for engagement beneath the lower inclined surfaces 26' of the bent up portions 16' to retain the clip against upward movement. A spike 22' driven 5 through the opening 19' into the tie engages in a recess 20' in the rear wall of the opening and bears against the rear face of the clip to force and retain the clip in rail gripping position. The recess 20' serves to 10 retain the spike in proper clip engaging position.

Various changes may be made in either 15 of the embodiments of the invention hereinabove described, without departing from or sacrificing any of the advantages of the invention as defined in the appended claims.

I claim:

1. A rail fastener including a tie plate having an opening therethrough provided 20 with an undercut wall, a rail clip having a thickened base portion for engagement beneath said wall and a portion projecting over an edge of the rail base, said opening being of sufficient width beyond said wall 25 to permit insertion and removal of said clip through the top of said tie plate, a spike in said opening behind said clip to retain said clip in rail securing position, and a recess in the rear wall of said opening for retaining 30 said spike in clip engaging position.

2. A rail fastener including a tie plate having an opening therethrough and a pair 35 of upwardly inclined portions overhanging a portion thereof, a rail clip having a thickened base portion for engagement beneath said inclined portions, said opening being of sufficient width beyond said portions to permit insertion and removal of said clip 40 through the top of said tie plate, a spike in said opening behind said clip to retain said clip in rail securing position, and a recess in

the rear wall of said opening for retaining said spike in clip engaging position.

3. A rail fastener including a tie plate having an opening therethrough and an undercut wall, a rail clip having upper and lower jaws for embracing an edge of the rail and a portion engageable beneath said wall, a spike in said opening behind said clip to retain said clip in rail securing position, and a recess in the rear wall of said opening for retaining said spike in clip engaging position. 45 50

4. In a rail fastener, the combination of a tie plate having an opening therethrough, and means including a spike in said opening for securing the rail to said tie plate, said opening having an inclined surface cooperating with said spike to force said securing means more firmly against the rail when 55 60 said tie plate tends to creep.

5. In a rail fastener, the combination of a tie plate having an opening therethrough, a rail clip in said opening, a spike in said opening for retaining said clip in rail gripping position, and inclined faces in the rear wall of said opening for forcing said spike 65 toward said clip by movement of said tie plate relative thereto.

6. In a rail fastener, the combination of a tie plate having an opening having undercut walls, a rail clip in said opening between said walls and retained thereby against climbing, a spike in said opening for retaining said clip in rail securing position, and inclined faces in the rear wall of said opening for forcing said spike more firmly 75 against said clip by movement of said tie plate lengthwise of the rail.

In witness whereof, I hereunto subscribe 80 my name this 3rd day of January, 1922.

EMERY M. McVICKER.
